UNITED STATES PATENT OFFICE.

HARRY A. REYNOLDS, OF FORD CITY, PENNSYLVANIA, ASSIGNOR TO PITTSBURGH PLATE GLASS COMPANY, A CORPORATION OF PENNSYLVANIA.

MACHINE FOR ROLLING PLATE-GLASS.

1,375,014.

Specification of Letters Patent. Patented Apr. 19, 1921.

Application filed May 26, 1920. Serial No. 384,461.

To all whom it may concern:

Be it known that I, HARRY A. REYNOLDS, a citizen of the United States, and a resident of Ford City, in the county of Armstrong and State of Pennsylvania, have made a new and useful Invention in Machines for Rolling Plate-Glass, of which the following is a specification.

The invention relates to apparatus or machines for rolling glass, such as employed in the manufacture of plate glass. The invention has for its principal objects the provision of an improved arrangement whereby the roll employed is prevented from being unequally heated between the operation of rolling successive sheets. In rolling mechanism as heretofore employed the proximity of one side of the roll to the table and the casting of the glass against the roll has caused such unequal expansion that the roll bulged appreciably, and when operated to roll out a sheet of glass produced an uneven thickness in the sheet. This difficulty arises not only with a solid roll but also with a water cooled roll, which latter, however, is distorted to a less degree. The present invention is designed to overcome or minimize this trouble, and briefly stated, this is accomplished by providing means for supporting the roll for rotation at the end of the table and providing means for rotating the roll in such position intermediate successive operations. One embodiment of the invention is illustrated in the accompanying drawings, wherein:

Figure 1 is a plan view of the apparatus, Fig. 2 is a side elevation, Fig. 3 is a section on the line 3—3 of Fig. 4 and Fig. 4 is a partial end elevation.

Referring to the drawings, 1 is the table supported on the base members 2 and 3, and 4 is the roll which rests during the operation of rolling the glass upon the rails or trams 5—5. At the further end of the table 45 is the usual apron 6 bridging the space between the end of the table and the receiving member 7 of the leer. The apron 6 is carried by the brackets 8 and 9 and is provided with the rails 9^a upwardly inclined as indicated in Fig. 2, so that when the roll reaches its extreme position at the left, as indicated in dotted lines in Fig. 2, a space is left beneath the roll for the passage of the sheet of glass and the stowing tool in shoving the

sheet of glass off of the table and into the leer.

The roll is moved over the table from the position indicated in full lines to the dotted line position by means of the sprocket chains 10 and the motor 11. The sprocket chains 10 are secured at one end to the apron by means of the hooks 12, and are looped around the pulleys 13 at the ends of the roll, as indicated in Fig. 2, their other ends being secured to the drums 14. These drums are rotated from the motor 11, a reducing transmission 15 and clutch 16 being interposed between the motor and the shaft 17, which carries the drums 14—14. This mechanism provides for moving the roll 4 from its right hand position (Fig. 2) to its left hand position, and for permitting the return of the roll to its starting position at the right of the table after the release of the clutch 16.

At the right hand end of the table are the rollers 18—18 and 19—19 carried by the transversely extending shafts 20 and 21. These shafts are mounted at their ends in the brackets 22^a, and the shaft 21 is provided with a sprocket 22 whereby it may be rotated. The rollers are located with their peripheries slightly above the rails 5—5, as indicated in Fig. 2, so that when the roll 4 arrives at the position indicated in Fig. 2, it is lifted slightly above such rails and is free to rotate upon the rollers 18 and 19.

The rollers 19—19 are rotated to cause the rotation of the roll 4 by means of the motor 23. This motor operates through the reducing transmission 24 to rotate the sprocket 25 which is geared to the sprocket 22 by means of the chain 26. In operation the roll 4 occupies the position indicated in full lines in Fig. 2 when the molten glass is teemed across the table adjacent the roll. The motor 11 is then operated to wind up the sprocket chains 10—10 and carry the roll to the left over the table and apron to the position indicated in dotted lines in Fig. 2, thus rolling out the sheet of glass. The stowing mechanism is then operated to carry the sheet of glass to the left beneath the roll and onto the receiving member 7 of the leer.

The roll may now be returned to its starting position and this is accomplished by releasing the clutch 16 and allowing the roll to move by gravity down the tracks 12 and along the table, its inertia upon striking

the rollers 18—18 being sufficient to carry it to the position indicated in full lines in Fig. 2. At this time the loops of chain around the pulleys 13 are removed therefrom and the motor 23 is operated to cause the rotation of the roll, and this rotation is continued until after the next body of molten glass is teemed on to the table for the succeeding rolling operation. This rotation of the roller gives it an opportunity to cool equally at all points of its circumference, there being no unequal cooling due to the proximity of one side of the roll to the table, such as is the case in the operation heretofore practised, when the roll remained in non-rotative position upon the tracks 5 during the period between successive teeming operations. Any unequal expansion of the roll due to the pouring of the glass adjacent one side of the roller is also reduced to a minimum due to the fact that the roller is being turned so that the point of contact with the molten glass is being shifted during the period of time in which the 25 glass is being poured or teemed in front of the roller and before its movement to the left is begun. As a result, the roll is in cross section a close approximation of a circle when the rolling operation begins, 30 and the sheet of glass produced upon the table is of substantially uneven thickness throughout. It is therefore possible to cast the sheet relatively thinner than has heretofore been possible since the removal of less 35 glass is necessary in the grinding operation than is the case where the sheets produced are of varying thickness due to the use of a bulged roll.

What I claim is:

- 40 1. In combination in glass rolling mechanism, a table, a roll mounted on the table for movement longitudinally thereof, means whereby the roll is supported for rotation at the end of the table, and means for rotating the roll while in such position intermediate successive casting operations.
- 45 2. In combination in glass rolling mechanism, a table, a roll mounted on the table for movement longitudinally thereof, roller means at the end of the table for receiving the roll, and means for rotating said roller

means to cause a rotation of the roll intermediate successive casting operations.

3. In combination in glass rolling mechanism, a table, a roll mounted on the table 55 for movement longitudinally thereof, means whereby the roll is raised from the table at the end of its travel and supported for rotation, and means for rotating the roll in such position. 60

4. In combination in glass rolling mechanism, a table, a roll mounted on the table for movement longitudinally thereof, a pair of roller members extending transversely of the table at its end and adapted to receive 65 the roll and support it for rotation out of contact with the table, and means whereby the roll is turned while in such position.

5. In combination in glass rolling mechanism, a table, a roll mounted on the table 70 for movement longitudinally thereof, a pair of roller members extending transversely of the table at its end and adapted to receive the roll and support it for rotation out of contact with the table, and means whereby 75 one of said roller members may be rotated to cause the rotation of the roll intermediate casting operations.

6. In combination in glass rolling mechanism, a table, a roll mounted on the table 80 for movement longitudinally thereof, power means, a releasable connection between said means and the roll for moving the roll along the table, means whereby the roll is supported for rotation independent thereof at 85 the end of the table, and a second power means for rotating the roll in such position when released from connection with the first power means. 90

7. In combination in glass rolling mechanism, a table, a roll mounted on the table for movement longitudinally thereof, power means for moving the roll along the table, means whereby the roll is supported independent of the table for rotation at the end 95 thereof, and a second power means for rotating the roll in such position between successive casting operations.

In testimony whereof, I have hereunto subscribed my name this 24th day of May, 100 1920.

HARRY A. REYNOLDS.
